REEL

Earl E. Berry, Beloit, Wis., assignor to Beloit Iron Works, Beloit, Wis., a corporation of Wisconsin

Application April 25, 1935, Serial No. 18,099

21 Claims. (Cl. 242—65)

This invention relates to paper making machinery, and has special reference to a reel of improved construction.

In the past there has been a certain amount of difficulty in handling paper as it emerges from the paper making machine. Two general systems have been employed for winding up the paper, each of which has been objectionable for one reason or another. The difficulties in winding up the paper have become more acute with the widening of the sheet and the increase in speed of the paper making machinery. According to one method, the roll of paper is wound up against a drum, the drum being driven. This arrangement has the advantage of ease in starting the sheet on the spool but is disadvantageous in that imperfections in the paper tend to produce poor reels of paper. If the paper comes of uneven caliper or has heavy and thin streaks, there is a tendency for wrinkles to form in the reel of paper which wrinkles frequently cannot be eliminated by subsequent operation. As the reel winds up to larger sizes, it will be evident that the heavier portions of the sheet tend to determine the size of the reel and the thinner sections are soft. The sheet is then stretched unevenly causing it to curl when finally unwound.

In distinction to this when the reel is wound up on the second or driven spool type of unit, since driving is not a matter of securing traction of the outside part of the reel upon a drum, the tension of the sheet as it is wound on the reel can be so regulated as to prevent these wrinkles and uneven conditions mentioned above. An advantage in this form therefore lies in the degree of control over the paper during the winding operations. However, the driven spool type offers difficulty in starting the paper on the winding spool, particularly under high speed operations and with wide sheets. If an attempt is made with the drum type of reel to wind up a comparatively soft roll, since the drive is by contact with the constant speed drum, some appreciable pressure is needed between the winding reel and the drum. This deforms the surface of the reel at the point of contact and since the drum forces itself into the soft reel to some extent, the drum is really acting upon the reel at a shorter radius than that at which the winding sheet of paper runs, the reel tends to drive faster than the sheet is coming to it, and the net result is that the sheet is wound up tighter than desired. In other words, it is not possible to wind as soft a roll with the drum type reel as with the driven spool type of reel.

An object of the invention is to provide a generally improved reel wherein the winding of the paper is started against a winding drum and the major part of the winding operation is conducted with the roll free of the drum.

Another object of the invention is the provision of a reel wherein the winding operation is started in one position against a winding drum and the started roll of paper is thereafter transferred to a second winding position at which the winding spool is driven at a speed to maintain a desired tension on the sheet.

A further object of the invention is the provision of a reel having improved means for bringing a spool into winding position, and improved means for transferring the spool from one winding position to another.

Another object of the invention is the provision of an improved method for winding paper as it emerges from a paper making or treating machine.

Other objects and attendant advantages will become apparent to those skilled in the art from the following description and the accompanying drawings, in which—

Figure 1 is a side view of the reel embodying my invention;

Fig. 2 is a view similar to Figure 1 showing some of the parts in section;

Fig. 3 is a vertical section through the device taken at right angles to Figure 1 showing the paper being wound in a position in which the spool is driven with the roll free of the starting drum;

Fig. 4 is a section substantially parallel to Fig. 3, and

Fig. 5 is a fragmentary view showing the position of the parts for transfer of the spool from the starting to the winding position.

What I now consider to be a preferred form of the invention is shown in the drawings wherein the numerals 6 and 7 designate the front and rear frame members. Brackets 8 and 9 having inwardly extending sleeves 11 and 12 are positioned on the top of the frame members 6 and 7. A winding drum designated generally by the numeral 13, and having a shaft 14 is carried in the brackets 8 and 9 on bearings 15 and 16. The shaft 14 and consequently the winding drum 13 is driven from one end of the shaft, as indicated at 17. The end 17 of the shaft is driven in the customary and well known manner from the paper making or treating machine with which the reel is associated so that the drum 13 will have a peripheral speed substantially equal to

the speed of the paper entering the reel. Since such drives are common and well known, I do not deem it necessary to enter into a detailed description of the same. Fixed arms 18 and 19 are attached to the top of the brackets 8 and 9 and extend outward on the receiving side of the machine as best shown in Figure 1. A spreader roll 21 extends between the ends of the arms 18 and 19 and is carried on bearings 22 supported on the outwardly extending ends of the arm by means of screws 23 having threaded engagement with collars 24 positioned between bifurcations 25 and 26 on the ends of the arm. Through rotation of the collar 24 the spreader roll may be adjusted to maintain the sheet taut throughout its width. The upper surfaces of the arms 18 and 19 serve to define a reserve position for the winding spool as will presently appear.

The spool, one of which is indicated generally at 27, comprises a central core 28 having a shaft 29, the ends of which project from the core 28, as shown at 31 and 32. The projecting ends of the shaft 29 each carry a bearing designated generally by the numerals 33 and 34. Each of the bearings has a plurality of annular recesses on its outer surface, as indicated at 35, 36 and 37 (Fig. 3), these recesses serving in the transfer of the spool from position to position. The outer recesses 35 of the bearings are of such width as to receive the upper edges of the arms 18 and 19 in the reserve position of the spool. The spools 27 are held in the reserve position by means of starting arms, designated generally by the numerals 38 and 39, positioned to register with the annular recesses 37 on the bearings 33 and 34. The starting arms are carried on hubs 41 and 42 positioned on the sleeves 11 and 12 and rotatable thereon. Gear segments 43 and 44 are also carried on the hubs 41 and 42 below the winding drum in a position to engage driving means for rotating the arms 38 and 39 so as to permit the spool to roll off the arms 18 and 19 into contact with the outer surface of the winding drum 13, as shown in Fig. 2, and to a subsequent transfer position as will presently be explained. The segments 42 and 43 are driven by spur gears 45 and 46 carried on the shaft 47 which is, in turn, journaled in the frame members 6 and 7. The front end of the shaft 47 extends beyond the frame member 6, as shown at 48, and carries a hand wheel 49 and a gear 51. The hand wheel serves for manual rotation of the shaft 47 while the gear 51 cooperates with a pawl 52 to normally lock the shaft 47 against rotation. The pawl 52 slides through a retainer 53 and is pivotally supported on a foot lever 54, as shown at 55, the foot lever being pivotally carried on the frame member 6, as shown at 56. A spring 57 acts to retain the pawl 52 in forward engaged position.

The sheet of paper enters the reel under the spreader roll 21 and passes over the drum 13, as best shown in Figure 1. The operator brings the parts into the initial winding position by depressing the foot lever 54 and rotating the hand wheel 49, thereby rotating the arms 38 and 39 into the position shown in Fig. 2. In this position, the core 28 of the spool is in surface contact with the winding drum 13 and the bearings 33 and 34 are in contact with the starting arms 38 and 39. The operator thereupon severs the paper on the offgoing side of the winding drum in the usual manner and causes it to follow the surface of the spool to start the paper winding on the 75 spool.

As soon as practicable after the winding is started in the initial winding position as described, the spool is transferred to a normal winding position in which the major part of the winding operation is conducted. In this position the spool is carried on a pair of winding arms designated generally by the numerals 58 and 59. Each of the winding arms has a yoke 61 attached to the upper end thereof and carried in ways 62 for adjustment transversely of the arms by means of a screw 63 threaded into a boss 64 on the yoke and carrying a hand wheel 65 for rotation of the screw. Through this means, the yoke may be adjusted on the winding arm to bring about proper alignment of the spool. The winding arms 58 and 59 are so spaced that the yokes register with the annular recesses 36 on the spool bearings 33 and 34. Thus, the spool bearings seat in the cradles 61 and the cradles in turn seat in the recesses 36 of the bearings so as to prevent endwise movement of the spool. The lower ends of the winding arms 58 and 59 are keyed as shown at 66 to a shaft 67 extending from front to back of the machine, the front end of the shaft being journaled in the frame member 6 and the back end of the shaft being carried in a frame member 68, the shaft being journaled in these two frame members for rotation. The front end of the shaft 67 carries a gear segment 69 positioned within the frame member 6 and meshing with a pinion 71 carried on a shaft 72 within the frame member 6. The shaft 72 also carries a gear 73 meshing with a pinion 74 on a shaft 75 which carries the end wheel 76 on the forward side of the frame member 6. It will be noted that the frame member 6 is carried outward, as shown at 77, to provide a housing or chamber for the gears just mentioned. A set screw 78 is positioned in the frame member 6 to abut the end of the gear segment 69 to determine the winding position of the arms 58 and 59 and a spring pressed pin 79 is positioned for reception in an opening 81 in the gear segment when the winding arm occupies the winding position to prevent accidental movement of the winding arm.

The spool is transferred from the starting or initial winding position by rotation of the hand wheel 76 in a direction to bring the winding arms 58 and 59 into a position adjacent the winding drum such as shown in Fig. 5. Thereupon, the hand wheel 49 is rotated in a direction to bring the starting arms 38 and 39 in a counter-clockwise direction facing Fig. 5, thereby permitting the spool to move along the surface of the winding drum in a counter-clockwise direction until the spool bearings 33 and 34 seat in the cradles 61 of the winding arms. Movement of the hand wheel 49 is continued until the starting arms reach a position free of the sweep of the spool as it moves into the winding position. Rotation of the hand wheel 76 in the opposite direction will then bring the winding arms into the normal winding position shown in Fig. 2.

Means are provided for driving the spool independently of the winding drum 13. This means is operative to establish driving relationship with the spool while it occupies its starting or initial winding position and to maintain the driving relation while the spool is transferred into the normal winding position and to complete the winding of the spool in the normal winding position. This means includes an arm 82 having one end fixedly carried on the shaft 67, the opposite end thereof projecting upward and carrying a bearing 83 75

longitudinally spaced from the end of the spool when the spool is seated in the cradles 61. A shaft 84 is carried in the bearing 83 and projects inward to a point spaced from the end of the spool, as shown in Fig. 3. The rear end of this shaft carries a pulley 85 driven by means of a belt 86 from a motor 87. A sleeve 88 having a flange 89 is carried on the front end of the shaft 84 for longitudinal sliding movement thereon, a key 91 10 preventing rotation of the sleeve with respect to the shaft. The flange 89 carries a flexible disk 92 coaxial with the shaft 84 and having a central opening 93 for the passage of the ends of the shaft upon longitudinal movement of the sleeve 15 88. Carried on the disk 92 is an electromagnet 94 adapted to engage a flange 95 keyed to the end 32 of the spool shaft. Conductors 96 and 97 of conductive material are adapted to be engaged by brushes, not shown, for the purpose of supplying 20 electrical energy to the electromagnet 94. These brushes are connected to a switch 98 for the purpose of controlling the supply of current to the magnet as will presently be described.

The sleeve 88 is moved from a position in which 25 the electromagnet engages the flange 95 to a retracted position by means of a collar 99 engaging the sleeve 88, a lever 101 pivotally engaging the collar 99 and being pivotally supported upon the arm 82, as shown at 102. The lever 101 is rotated 30 about the pivot point 102 by movement of a rod 103 extending from front to back of the machine, as shown in Fig. 3 and 4, the rod being manually movable longitudinally by means of a handle 104. The rod 103 is maintained in either of two opposed 35 limit positions by means of a spring pressed toggle 105 acting between the arms 82 and the end of the rod 103. The rod 103 also carries a finger 106 adapted to actuate the lever of the switch 98 so as to shut off the current to the electromagnet 94 40 when the rod occupies its forward position as shown in Fig. 4, and to close the circuit to the magnet when the rod occupies the rearward position, as shown in Fig. 3.

Driving connection to the spool is preferably 45 established when the winding arms 58 and 59 occupy the position shown in Fig. 5. This is accomplished by inward movement of the handle 104, whereby the sleeve 88 is moved so as to engage the electromagnet 94 with the flange 95 of the 50 spool and simultaneously close the switch 98, whereupon the electromagnet is energized. The driving motor 87 is preferably designed to run continuously and to be controlled by an independent switch, positioned as may be desired by the 55 operator.

In accordance with the usual practice, the spool, when occupying the normal winding position, is driven at a rate to maintain a constant or a predetermined tension on the sheet being wound. 60 Any of numerous well known devices may be employed for accomplishing this drive. Since the specific form of drive is not a part of the present invention, I have not shown the details of the construction whereby the motor 87 is caused to drive the spool to maintain constant tension on the sheet. However, one satisfactory form of such drive is known as the "Reliance constant-tension drive", and comprises a generator driven from the winding drum 13, the generator being connected to the motor 87 in such manner as to give constant tension in the sheet. This type of drive in both electrical and hydraulic mechanism is well known in the art.

75 In use, the operator carries the parts through

the following cycle: Assuming the parts to be in the position shown in Figure 1 and the spool of paper being wound to its desired diameter, the operator rotates the wheel 49, thereby moving the starting arms 38 and 39 into the position shown in Fig. 2, whereupon the spool carried in the reserve position on the arms 18 and 19 rolls down into the initial driving position. The sheet is then severed on the offgoing side of the winding drum and caused to follow the newly positioned spool. The handle 104 is then drawn outward to the position shown in Fig. 4, releasing the drive on the wound roll. The wound roll may then be lifted from the cradle by a crane or other suitable means. In the meantime, the winding 10 of the sheet has been well started on the newly positioned spool so that the winding arms 58 and 59 may be swung into the position shown in Fig. 5 and the new spool received within the cradle. The independent drive for the spool is 15 then engaged by actuation of the handle 104 and the spool is brought into the normal winding position by rotation of the wheel 16. Next, the starting arms 38 and 39 are returned to the position shown in Figure 1 and an empty spool positioned in the reserve position on the arms 18 and 19, thereby completing the cycle of operation.

It will be seen that according to my invention the winding operations are started with the spool operating against a winding drum under which 30 circumstances the sheet may be started on the spool in a smooth and uniform manner without the loss of a great deal of paper in accomplishing the starting operation. Likewise, the sheet starts smoothly and evenly on the roll so that lumps 35 and bulges are not produced at the center of the roll, resulting in the waste of a considerable amount of paper when the sheet is re-wound. After the initial winding of the sheet, the spool is transferred as soon as practicable into the normal winding position in which the spool and the roll of paper are free of the winding drum. In this winding position, the best winding characteristics are obtained and the winding operations are free of the difficulty commonly associated 45 with the winding of a roll against the surface of a winding drum, such, for example, as the production of wrinkles in the sheet and soft spots in the roll.

Another advantage of my improved reel lies in 50 the ease with which the paper can be handled when a break has occurred. With the old driven spool type of reel, when a break occurs the operators have to carry the sheet around the moving spool by hand and fold the end in between the 55 sheet and the reel to start the winding up operation again. At any appreciable speed this is a very difficult operation and usually is accompanied by a considerable loss of paper. With the reel of my invention, if a break should occur 60 the partially wound reel of paper is lowered into contact with the drum, and when the sheet is ready to be placed on the reel again, it will be passing between the partially wound reel and the drum, thus controlling the draw from the 65 paper machine or its calenders. The operators then need only tear off any excess paper and throw the end of the sheet up around the partially wound reel by hand or by means of an air jet in order to start winding up again. As soon 70 as the end is securely wound onto the reel, the reel is taken away from the drum as when starting a new one.

Another advantage of my improved construction is the fact that it permits getting a good 75

hard start when the paper is wound on a new spool whereupon the tension may be relieved as the reel builds up. The hard start is, of course, secured when the new spool is on the drum and the sheet is being started around it, and then by moving the arm 38 and 39 down from the starting point gradually, the tension with which the paper is wound can be somewhat diminished to the point where the spool is transferred to the arms 58 and 59 and from the time when these arms take the spool, the tension can be still further reduced by operating whatever drive is supplied for the spool when in these arms. This feature of a hard start and a controlled tension during the balance of the winding is something which cannot be readily secured with the ordinary driven spool type of winder because the sheet cannot be taken continuously from the machine and placed on the spool in its initial layers tight enough to give the hard start that is required. It has frequently been said that no reel is better than the start, and when the starting layers are too loose the subsequent layers cannot be hardened up without getting into wrinkles and other difficulties, and it is frequently the case that the comparatively loose layers at the spool cause the paper to move sidewise on the reel, sometimes spoiling the entire reel.

I have provided improved means for the transfer of the spool from position to position during the winding operation and for retaining a fresh spool in a reserve position. I have also provided improved means for holding a fresh spool in a reserve position and for bringing the new spool into operative position with respect to the drum and into a position for the transfer of the spool from its initial winding position to its normal winding position.

Another feature of the invention lies in the provision of improved means for supporting the spool in its normal winding position and of improved means for affecting the drive of the spool in its normal winding position and during the transfer of the spool from its initial position to its normal winding position.

While I have thus described and illustrated a specific embodiment of the invention, I am aware that numerous alterations and changes may be made within the spirit of the invention, and I do not wish to be limited except as required by the prior art and the scope of the appended claims, in which—

I claim:

1. The combination in a paper winding machine, of a driven winding drum, means for holding a winding spool in an initial winding position in surface contact with said drum, means for transferring the spool from said initial position to a normal surface free winding position, and means for driving said spool in the latter position with a free peripheral surface.

2. The combination in a paper winding machine, of a driven winding drum, means for holding a winding spool in a reserve position, means for bringing the spool into initial winding position in peripheral contact with said drum, means for transferring the spool while winding from said initial position to a normal peripherally free winding position, and means at the axis of said spool for driving the same in the latter position.

3. The combination in a paper winding machine, of a driven winding drum, means for holding a winding spool in an initial winding position against said drum, means for establishing a driving connection with said spool while in said ini-

tial winding position to drive the same independently of the drum, and means for transferring said spool from said initial position to a normal winding position free of said drum.

4. The combination in a paper winding machine, of a driven winding drum, means for holding a winding spool in an initial winding position against said drum, means for transferring said spool from said initial position to a normal winding position free of said drum, an independent driving means associated with said transfer means, and means for establishing driving connection between said independent driving means and said spool prior to the removal of said spool from said initial winding position.

5. The combination in a paper winding machine, of a driven winding drum, means for holding a spool in peripheral winding relation with said drum, means for transferring said spool to a normal winding position free of said drum, and means for driving said spool to wind the paper thereon when the spool has been removed from the drum and while it is being transferred.

6. A paper winding machine comprising in combination, a driven winding drum, a spool adapted to be held in initial winding position against said drum, means for transferring the winding spool from said initial position to a position remote from said drum, means for supporting the spool in said initial position, said means being movable to deposit this spool in said first mentioned means, and means for driving said spool while it is being transferred.

7. A paper winding machine comprising in combination, a driven winding drum, a spool adapted to be held in an initial winding position against the drum, means for transferring the spool from said initial position to a normal winding position remote from said drum, means for supporting the spool in said initial position, said means being movable to deposit the spool in said first mentioned means, and means for driving the spool after the deposit thereof in said first mentioned means including clutch means operable to make and break the driving connection.

8. A paper winding machine comprising in combination, a driven winding drum, a spool adapted to be held in initial winding position against the drum, means for transferring the spool from said initial position to a normal winding position remote from said drum, means for supporting the spool in said initial position, said means being movable to deposit the spool in said first mentioned means, driven clutch means movable with said transferring means, and manually operable means for engaging and disengaging the clutch means with the end of the spool to establish driving connection therewith to drive the spool when the same is moved from said initial position.

9. A paper winding machine comprising in combination, a driven winding drum, a spool adapted to be held in initial winding position against said drum, means engaging the ends of the spool for transferring the same from said initial position to a normal winding position, a magnetic clutch having a driving element mounted for movement with said last mentioned means and a driven element on said spool, and manually operable means for actuating said clutch to selectively drive the spool.

10. The method for winding paper emerging from a paper making or treating machine which includes the steps of starting the winding of the sheet on a spool with the spool in surface driving contact with a driven winding drum, and

moving the spool out of contact with the drum shortly after winding of the sheet has started for the completion of the winding of the spool with a free peripheral surface.

5 11. The method for winding paper emerging from a paper making or treating machine, which includes the steps of starting the winding of the sheet on a spool with the spool in surface driving contact with a driven winding drum, establishing a second driving connection at the axis of the spool, thereafter moving the spool out of contact with the drum shortly after winding of the sheet has started for the completion of the winding of the spool under said last mentioned 10 driving connection with the periphery of said spool free.

12. A method for winding paper emerging from a paper making or treating machine comprising feeding winding spools in succession into 20 winding contact with a driven winding drum, starting the winding of the paper on said spools while in contact with said drum, and thereafter moving the spools out of contact with the drum for the completion of the winding operations 25 with the periphery of the spool free of winding contacts.

13. The combination in a paper winding machine of a driven winding drum, means for holding a winding spool in an initial winding position against said drum, means for transferring said spool from said initial position to a normal winding position free of said drum, driving means independent of said drum for driving said spool, and means for establishing driving connection between said independent driving means and said spool prior to the removal of the spool from said initial winding position whereby the drum acts to synchronize the speeds of the independent driving means and the spool, and the independent driving means is connected while the spool is being transferred from its initial winding position against the drum to its normal winding position disengaged from the drum.

14. The combination in a paper winding machine of a driven winding drum, means for holding a winding spool in an initial winding position in peripheral contact with said drum, means for transferring the spool from said initial position to a normal peripherally free winding position, and means at the axis of said spool for driving the same in the latter position and during the transfer thereof from the initial to the normal winding position.

15. In a paper winding machine, the method 55 consisting in starting winding the paper from a driven winding drum onto a winding spool while the latter is in winding contact with the former, withdrawing the spool and the roll of paper started thereon out of contact with the winding drum, and rotating the spool to com-

plete the winding of the roll out of surface contact with any form of winding drum.

16. In a paper winding machine, in combination, a winding drum, a winding spool, means for carrying the spool in reserve position and operative for moving the spool into initial winding position on the winding drum, means other than the drum for driving said spool, and means operative to establish driving relationship between the last mentioned means and the spool while the latter occupies its initial winding position, to transfer the spool to a normal winding position remote from the winding drum, to maintain driving of the spool while it is being transferred to said normal winding position, and continuing 15 to drive the spool in said normal winding position.

17. In a paper winding machine, in combination, a driven winding roll, a winding spool, a spool carrying cradle mounted to oscillate about 20 a given center to carry the winding spool from a starting position in cooperation with the winding drum to a normal winding position remote from the drum, and means for driving the winding spool while it is being moved between said 25 positions.

18. In a paper winding machine, the combination set forth in claim 17, including a spool driving member substantially coaxial with the center about which the cradle oscillates. 30

19. In a paper winding machine, in combination, a driven winding drum, a winding spool, means for holding the spool in initial winding position on the winding drum, a spool carrying cradle mounted to oscillate about a given center 35 to carry said winding spool from said initial winding position to a normal winding position remote from the winding drum, and means for driving the winding spool while it is being carried on said cradle in said normal winding position. 40

20. In a paper winding machine, in combination, a driven winding drum, a winding spool having a shaft, means for holding the winding spool in an initial winding position against said drum, means for transferring said spool from said initial position to a normal winding position free of said drum, and driving means adapted to be clutched to the winding spool shaft for driving the spool, continuously from the time a roll has been initially wound until the winding is completed in the normal winding position. 45

21. In a paper winding machine, the combination set forth in claim 20, in which the spool driving means is mounted to be moved back and forth between said initial winding position and said normal winding position and to be de-clutched from the spool in the normal winding position and clutched to another spool in the initial winding position. 55

60
EARL E. BERRY.
